Primary Examiner—B. J. Bullock[57] CLAIM

The ornamental design for a hanging organizer for hair bows, as shown.

DESCRIPTION

FIG. 1 is a front elevational view of a hanging organizer for hair bows showing my new design, the rear being a mirror image thereof;

FIG. 2 is a right end elevational view of the hanging organizer for hair bows, the left end being substantially a mirror image thereof;

FIG. 3 is an enlarged view showing the grid design in greater detail; and,

FIG. 4 is a perspective view of the hanging organizer for hair bows.
